UNITED STATES PATENT OFFICE.

ALBERT N. HOPKINS, OF DULUTH, MINNESOTA, AND FRANKLIN P. HOPKINS, OF HYATTSVILLE, MARYLAND, ASSIGNORS OF ONE-HALF TO MARCUS W. BATES, OF ST. PAUL, MINNESOTA.

GRAIN-CAR DOOR.

SPECIFICATION forming part of Letters Patent No. 627,852, dated June 27, 1899.

Application filed September 19, 1898. Renewed May 12, 1899. Serial No. 716,516. (No model.)

To all whom it may concern:

Be it known that we, ALBERT N. HOPKINS, of Duluth, in the county of St. Louis and State of Minnesota, and FRANKLIN P. HOPKINS, of 5 Hyattsville, in the county of Prince George's and State of Maryland, have invented a new and useful Improvement in Grain-Car Doors, of which the following is a specification.

This invention is an improvement in grain-10 doors for railway-cars, and has for an object to provide a simple inexpensive construction which will be efficient and durable, will form a tight closure for the grain, and can be easily opened.

15 The invention consists in certain novel constructions and combinations of parts, as will be hereinafter described, and pointed out in the claims.

In the drawings, Figure 1 is a side elevation 20 of a door provided with our improvements. Fig. 2 is a vertical section thereof on about line 2 2 of Fig. 1. Fig. 3 is a horizontal section on about line 3 3 of Fig. 1, and Fig. 4 is a detail view illustrating the adjusting connection and the seat and bearings for same.

25 In car-doors of this class it is important to provide a door which will open outward, may be swung inward and upward when the car is empty, may be securely locked in closed position, and especially that the operating devices for setting and releasing the locking devices shall be supported and braced in such manner as to be durable and operate with reasonable certainty and ease.

35 The car A may be of any ordinary construction having the doorway B. At the sides of this doorway we provide the upright plates C, preferably of metal and arranged one at each side of the doorway B. These 40 plates C form bearing-abutments for the locking and sealing plates presently described.

The door D is made of such size as to permit it to pass freely between the plates C and is suspended by the bars E, to which the door 45 is hinged at F, so the door D can swing outward on the pivotal connection E' of the bars E with the car or inward on its hinged connection with the bars E.

The door D extends at D' above the hinged

connection F, and such extension may be of 50 any desired length to permit the loading of the car to any desired height.

When the car is empty, the door and its hanger-bars E can be folded up, as shown in dotted lines, Fig. 2, and secured by a hook G 55 or other suitable fastening. In so folding the door and bars E the door may be first turned upward from its lower end, as indicated by the arrow-line H, swinging on the pivot F as a center, and then the bars E and door D be 60 jointly swung on the arrow-line H', the connection E' being the center of such movement.

To lock the door in closed position, we provide the locking and sealing plates I I, arranged on the outer side of the door at its 65 opposite edges and extending from top to bottom of the said door. These plates I are movable inward and outward and may be projected beyond the edges of the door to bear in rear of the abutment-plates C, as shown 70 most clearly in Fig. 3. In this position the plates I lock the door from outward movement and seal the contents of the car against leakage and also lock the door in closed position. These plates I are adjusted laterally 75 in and out by means of the adjusting connection J, which is suitably threaded at its ends to receive the reversely-threaded ends of the rods I', whose outer ends are connected with the plates I. These rods I' are longitudinally movable in guides K and L.

The adjusting connection J is seated in a recess J' and may be turned by the sliding rod J² to set the locking and sealing plates I in or out, as desired. 85

The guides L for the rods I' have base-plates L' secured to the door and lying at their inner edges on opposite sides of and flush with the side walls of the recess J' and bear on opposite sides of the connection J, forming a 90 metallic bearing for the ends of said connection, operating to secure it properly in position and permitting it to be easily turned as desired.

A handle M on the inner side of the door 95 facilitates manipulating the door in folding and unfolding the same.

The door is simple in construction, may be

easily operated, and will be found practical and efficient.

Having thus described our invention, what we claim as new, and desire to secure by Letters Patent, is—

- 5 1. In a car-door the combination of the car having its doorway provided with the upright bearing-plates, the door having a recess for the adjusting connection, the locking and sealing plates movable on said door into and out of position to abut the said upright plates, the rods connected with said plates, the adjusting connection threaded to said rods, and the guides for said rods having base-
10 plates arranged on opposite sides of the recess for the adjusting connection in position to bear against the opposite ends of the adjusting connection all substantially as and for the purposes set forth.
- 15 2. In a car-door the combination with the

door having the recess in its outer face and the locking and sealing plates thereon at its opposite edges of the adjusting connection seated in said recess the rods secured to the locking-plates and threaded into the adjusting connection and the guides for said rods having base-plates lying on opposite sides of and forming bearings for the adjusting connection substantially as set forth. 25
